Henry Harness
ATTORNEY

UNITED STATES PATENT OFFICE

RUSSELL M. KINCAID, OF DETROIT, MICHIGAN, ASSIGNOR TO CHRYSLER CORPORATION, OF DETROIT, MICHIGAN, A CORPORATION OF DELAWARE

POLISHING MACHINE

Application filed July 27, 1929. Serial No. 381,622.

This invention relates to a polishing machine, and more particularly to a machine in which a full sized vehicle body may be inserted and the major portion of its surface 5 polished at one time.

An important object of the invention is to provide a machine which will polish or sand the major portion of the vehicle body mechanically, requiring very little manual 10 labor in finishing the body after it has been removed from the polishing machine.

Another object of the invention is to provide a machine which readily adapts itself to the irregular surfaces of a vehicle body 15 and to arrange the abrasive material in such a manner that all portions thereof are resiliently pressed against the surface of the body by equal tension on all portions.

Other objects and advantages of the invention will more fully appear from the following description taken in connection with the accompanying drawings in which:

Fig. 1 is a side elevation of a machine showing one adaptation of my device.

Fig. 2 is a plane view of Fig. 1.

Fig. 3 is a fragmentary view showing a portion of the machine and a vehicle body in section.

Fig. 4 is a detail showing one of the abrasive units in section.

Fig. 5 is a side view of a portion of the abrasive units showing the arrangement of the abrasive elements.

Referring now to the drawings and more particularly to Fig. 1, I have provided a 35 rectangular frame 10 supporting at one end thereof a driving member such as an electric motor 12. A power transmission mechanism is shown at 14, and is adapted to be driven by the motor 12 through a belt 16.

As shown in Fig. 2, the frame 10 conforms generally to the curvature of a vehicle body, and one side of the frame is pivoted as at 18 45 on a base 20 to swing outwardly for the reception of a vehicle body. The upper longitudinal member of the frame 10 is provided with guide blocks 22 and the lower longitudinal member is provided with guide blocks 24, and longitudinal track members 26. Be-

tween the guide blocks 22 and 24, I have supported abrasive units which are comparatively large and adapted to cover one panel of the vehicle body. Each unit comprises a frame work 28 and having plates 30 55 for detachably receiving the abrasive elements and their holding mechanism which will be hereafter more fully explained. At the upper and lower edges of each unit, I have provided rollers 32, in a horizontal 60 plane which are in engagement with the guide blocks 22 and 24 respectively, and on the under surface of each frame unit 28, I have provided rollers 34 which are carried by the track members 26. Each unit is connected together by links 36.

On the forward frame member 28, I have provided a connecting rod 38 which is mounted on an eccentric 40 carried by a shaft 42 and driven by the transmission mechanism 14. It will be understood that when the shaft 42, is rotated, the eccentric 40 reciprocates the rod 38, and it in turn, through its connection to the frame member 28, reciprocates the frame 28 in a horizontal plane along the sides of the vehicle body. The other units, being attached to the forward unit through links 36, move in a horizontal plane with the forward frame member 28.

It will be understood that the number, size and shape of these units may be varied, as for example, the rear unit 44 is shown considerably smaller than the intermediate units for polishing a smaller panel such as the 80 panel above the wheel house.

As shown in Fig. 2, one side of the frame 10 is pivotally mounted, and the opposite side is stationary. To the stationary side, I have pivotally mounted another panel for polishing the rear surface of the vehicle body.

In the illustrated embodiment of this device, a separate driving mechanism is shown as at 46 for reciprocating the abrasive unit. A bolt 48 pivotally mounted on the one side 95 of the supporting frame 10 is adapted to be engaged in a bracket 50 for locking the rear unit to the frame 10 after a vehicle body has been placed in the machine. The movable frame 10 is also provided with a bolt 52 which 100

is secured to a stationary member 54 on the base 20 of the machine. It will be understood that when it is desired to polish a vehicle body, the pivotally mounted frame members, one at the side and the one at the back, may be swung out of their normal position and the body inserted against the stationary member 10. The swinging panels are then brought into engagement with the body and locked in position. The motor is then started and the abrasive units reciprocate in a horizontal plane to polish the several panels or parts of the vehicle body.

Referring more particularly to a specific construction for resiliently urging the abrasive blocks against the surface of the body, I have shown a rigid plate 56 supported on the frame 28 by brackets 30. This plate 56 conforms generally to the curvature of the body and forms a backing plate for a plurality of springs 60. A flexible pad 62, preferably of rubber is positioned on the outer ends of the springs 60 and is adapted to receive a plurality of abrasive blocks 64, preferably of cylindrical formation arranged in vertical rows and in staggered relation.

If desired, the rubber pad 62 may have a backing member such as a leather pad 66, the two being secured together by bolts 68. The opposite ends of the springs 60 are provided with metallic members 70 to form suitable seats for the ends of the spring. Angle members 72 are provided, one on the plate 56 and one on the leather pad 66 in engagement with each other, to support the abrasive elements vertically. Angle members 74 extending at right angles to the angle member 72 have been arranged in a vertical position to guide the abrasive elements horizontally.

40 The abrasive elements are comparatively thick and are formed of such material that will wear down fast enough to prevent filling or clogging of the abrasive material with particles removed from the surface of the body, but is hard enough to prevent wearing away too rapidly. The abrasive elements are detachably secured to the several units by being frictionally held in openings in the rubber pad 62.

50 Various changes including the size, shape and arrangement of parts may be made without departing from the spirit of my invention, and it is not my intention to limit its scope other than by the terms of the appended claims.

What I claim is:

1. A machine of the class described, comprising a frame construction having side portions spaced to receive a vehicle body therebetween, a plurality of interconnected movable members on each side portion and a plurality of abrasive members on said movable members.

60 2. A machine of the class described, comprising oppositely spaced movable members,

a rigid plate on each of said members, a flexible pad adjacent the inner surface of each rigid plate, resilient means between said pad and said plate and a plurality of abrasive members on the inner surface of said flexible pads.

3. A machine of the class described, comprising a supporting structure having two side portions oppositely spaced for the reception of a vehicle body therebetween, a plurality of movable members on each of said portions conforming generally to the contour of the vehicle body, and a plurality of abrasive members on the inner surface of each movable member.

4. A machine of the class described, comprising a supporting structure having two side portions oppositely spaced for the reception of a vehicle body therebetween, a plurality of movable members on each of said portions conforming generally to the contour of the vehicle body, a flexible pad resiliently supported on the inner surface of each movable member, and a plurality of abrasive members on the inner surfaces of said flexible pads.

5. A machine of the class described, comprising a frame structure having side portions spaced for the reception of a vehicle body therebetween, a plurality of reciprocating members guided in the side portions of said frame structure, a rigid plate on each of said reciprocating members conforming generally to the shape of the side walls of the vehicle body, a flexible pad at the inner surface of said rigid plate, resilient means between said flexible pad and said rigid plate and a plurality of abrasive members detachably supported on the inner face of said flexible member.

6. A machine of the class described, comprising a frame structure having side portions spaced for the reception of a vehicle body, one of said side portions being pivotally mounted, a plurality of movable members carried by said side portions, and abrasive members on the inner surface of said movable members.

7. A machine of the class described, comprising a frame structure having side portions and an end portion, said side portions being oppositely spaced and said end portion being pivotally mounted relative to said side portions for the reception of a vehicle body between said side portions, a plurality of abrasive members mounted for movement in said side and end portions, means for moving said abrasive members, and means for resiliently urging said abrasive members against the walls of the vehicle body.

8. A machine of the class described, comprising a supporting structure having side portions spaced for the reception of a part to be polished, a plurality of movable members conforming generally to the surface of

the part to be polished, means for moving said movable members, a plurality of abrasive members on the inner surface of said movable members, and means for urging said abrasive members into engagement with the surface of the part to be polished, each of said members being urged inwardly against the surface with substantially equal force.

RUSSELL M. KINCAID.
